UNITED STATES PATENT OFFICE.

JOHN AUSTIN BEST, OF AUGUSTA, GEORGIA.

CARD FOR INDEXES.

1,278,834.

Specification of Letters Patent. Patented Sept. 17, 1918.

Application filed December 6, 1917. Serial No. 205,758.

To all whom it may concern:

Be it known that I, JOHN AUSTIN BEST, a citizen of the United States, and a resident of Augusta, in the county of Richmond 5 and State of Georgia, have invented a new and useful Improvement in Cards for Indexes, of which the following is a specification.

My present invention relates generally to 10 indexes, and more particularly to card indexes, my object being the provision of a card for such indexes, adaptable as either a sub-index card or a record card, and whereby a system indexed by means of the 15 usual tabbed index or guide cards for instance, may be expanded and further indexed to two additional letters throughout, either as to letters of surnames, initials, or the like.

20 A further object is to accomplish the above by means of cards of the same construction, whose arrangement permit of their use at any desired point within an index.

Generally speaking, my invention resides 25 in an index card having the letters of two alphabets along its upper edge, so arranged in respect to one another and the card that by cutting portions of the two series away, the user may expose any two letters of the 30 alphabet desired at the outermost edges, and with cuts of but a single and the same depth, so as to adapt the card for use as a sub-index card where it is necessary for the letters to show between the upper edges of the 35 reference cards and the tabs of the main index or guide cards.

A still further object of my invention is 40 to provide a card so constructed as to facilitate the cutting thereof to expose desired letters of the two alphabetical series.

In the accompanying drawings illustrating 45 my invention and forming a part of this specification,

Figure 1 is a face view of an index card constructed in accordance with my invention previous to the cutting thereof for indexing purposes.

Fig. 2 is a similar view of a card after 50 it is cut for indexing purposes and ready for use, and

Fig. 3 is a similar view of another card in the nature of a sub-index card for instance, after the latter has been cut, the cut portions being indicated in broken lines.

55 Referring now to these figures and particularly to Fig. 1, my invention proposes

a card 10 of rectangular shape and the body portion of which is of the same size as the record card in connection with which the card 10 is utilized, the card as shown in 60 Figs. 1 and 2, being particularly adapted as a sub-index card, between the usual single letter tabbed index or guide cards.

When so intended for use, the card 10 has an extended strip 11 along its upper 65 edge above a line 12, which latter defines the height of the record cards in connection with which the card 10 is to be utilized, the strip 11 being blocked off as shown, to facilitate cutting between the letters of the 70 two series 13 and 14 which it will be noticed are both above the horizontal line 12 and thus in the same horizontal plane.

Each of the series of letters 13 and 14 forms a complete alphabet of which the initial letter is adjacent to the center of the 75 card 10, each alphabet progressing regularly toward one of the side edges of the card.

By thus providing the card 10 with an extension strip 11 on which the two alphabets 80 are disposed, and arranging these alphabets in respect to the card and to one another as described, it is obviously convenient to adapt the card 10 for use as a sub-index card between the main tabbed guide cards and the 85 record cards, and that desired letters of both of the series 13 and 14 may be exposed at the sides by removal of portions of the two series through vertical cuts extending to the line 12 and horizontal cuts along said line 90 for portions of its length.

Thus, as seen in Fig. 1, the two series 13 and 14 are fully exposed between the upper edges of the guide cards (not shown) and the tabs of guide cards, one of which is seen 95 in dotted lines at 15.

Furthermore, where it is desired to index as to the second and third letters of the surname and where it is desired to index the surname seen in Fig. 1 in accordance 100 with this rule, the series 13 is cut on the line between "R" and "S", and then along the line 12 to the letter "R" which will remove that portion of the series 13 outwardly beyond the letter "R" and expose the latter 105 at the then left-hand side of the letters, and the series 14 is then cut along the line between "A" and "B" and along line 12 to remove that portion of the series outwardly beyond the letter "A."

110 Similarly, when it is desired to index a surname as seen in Fig. 2, as to the second

and third letters thereof, that portion of the series 13 up to its initial letter is removed, as indicated in the figure, and that portion of the series 14 is removed up to the letter 5 "D", so that the second and third letters of the surname "a" and "d" will be respectively exposed at the left and right-hand edges of the letter series, with cuts of the same depth so that both of these letters being in the 10 same horizontal plane, will be exposed to the view of the operator between the tabs 15 of the guide cards and the upper edges of the record cards, which latter as before stated, coincide with the line 12.

15 It is obvious that my invention as thus described is equally adaptable for utilization in the form of card 16 such as seen in Fig. 3, the series of letters being in the same arrangement at the upper edge thereof as in 20 connection with the card 10 of Figs. 1 and 2, and that in addition thereto and in order to facilitate the cutting to expose desired letters of the two series, the card 16 may be 25 provided with slots 17 extending inwardly from its side edges in the same horizontal plane below the plane of the two series of letters, the inner ends of which slots terminate at opposite sides of the center of the card, whereby any desired letters may be exposed in the two series, each with but a single vertical cut from the upper edge of the card to the respective slots 17.

It is obvious that in view of the foregoing, my invention proposes a card of but a 30 single construction in either use, so that a series of cards 10 or a series of cards 16 will place the user in possession of means where-

by to expand a card index throughout each of its divisions, not only as to letters of the surname as in Figs. 1 and 2, but also as to 40 initials and the like, as suggested by the arrangement of Fig. 3.

I claim:

1. A card of the character described for indexes, having series of letters along its 45 upper edge portion, forming two separate alphabets in the same horizontal plane, each of said alphabets having its initial letter adjacent to the center of the card and progressing regularly toward one of the side edges 50 of the card, whereby desired letters of both alphabets may be reached by cuts of the same depth and from opposite sides of the card, the said card having slots extending inwardly from its side edges in the same horizontal plane, below the plane of the said letters, and terminating at opposite sides of 55 the center of the card, for the purpose described.

2. A card of the character described for 60 indexes, having two series of index letters along its upper edge and forming two separate alphabets progressing from their first to last letters in relatively opposite directions and toward the side edges of the card, said 65 card having separate slots extending beneath the two series of letters from its side edges, whereby portions of each alphabet may be removed by a single vertical cut to one of the said slots.

JOHN AUSTIN BEST.
